UNITED STATES PATENT OFFICE.

JOHN LAZIER MACDOWALL, OF PERTH AMBOY, AND WILLIAM KIPP BASSFORD, OF METUCHEN, NEW JERSEY.

SAFETY DEVICE FOR OIL HEATERS AND LAMPS.

1,343,217.

Specification of Letters Patent. Patented June 15, 1920.

Application filed August 9, 1919. Serial No. 316,407.

To all whom it may concern:

Be it known that we, JOHN L. MACDOWALL and WILLIAM K. BASSFORD, both citizens of the United States, and residents, respectively, of Perth Amboy and Metuchen, in the county of Middlesex and State of New Jersey, have invented new and useful Improvements in Safety Devices for Oil Heaters and Lamps, of which the following is a specification.

This invention relates in general to safety devices for oil heaters and lamps and more particularly to a device of this character which will immediately extinguish the flame of the heater or lamp in case the same is tipped over or dropped, so as to prevent the oil reservoir from catching fire or exploding.

The objects of the invention are to provide a safety device of the character described which will automatically form a substantially air tight chamber about the flame of an oil heater or lamp so as to immediately extinguish the flame when the heater or lamp is accidentally tipped over or dropped; to provide a device which will also automatically extinguish the flame when the heat produced in the heater or lamp reaches a predetermined degree; to provide a device of this character which can be easily and quickly applied to any conventional type of oil heater or lamp burner without modification or alteration of the heater or lamp; to obtain a device which is simple and inexpensive in construction and to obtain other advantages and results as may be brought out in the following description.

Referring to the accompanying drawings, in which like numerals of reference indicate the same parts throughout the several views,

Figure 1 is a vertical sectional view through the lower portion of a conventional oil heater, showing one embodiment of the invention applied thereto;

Fig. 2 is a horizontal sectional view on the line 2—2 of Fig. 1;

Fig. 3 is a detail perspective view of the stop ring;

Fig. 4 is a vertical sectional view through a conventional oil lamp burner, showing another embodiment of the invention applied thereto;

Fig. 5 is a similar view taken at right angles to that of Fig. 1;

Fig. 6 is a top plan view thereof;

Fig. 7 is a top plan view with the air deflecting cap removed;

Fig. 8 is an enlarged fragmentary sectional view, showing the invention in an extinguishing position over the wick, and

Fig. 9 is a detail perspective view of the flame extinguisher shown in Figs. 4 to 8 inclusive.

Specifically describing the embodiment of the invention illustrated by Figs. 1 to 3, inclusive, the reference character A designates the base of a conventional type of oil heater, said base removably receiving and supporting the oil reservoir B. A vertically disposed annular wick tube C is carried by the oil reservoir B and receives an annular wick D which projects downwardly into the reservoir B into the oil, conventional wick adjusting means being indicated at E. A hollow air and flame spreading member F is fitted loosely within the center of the annular wick tube so as to allow air to pass upwardly into the burner to produce proper combustion, said member F being provided with a flame spreading flange G which surrounds the member F and lies over the top of the wick D, a series of air holes H being arranged between this flange G and a similar flange I arranged above the flange G to further spread the flame and enhance combustion. A casing K is mounted upon the base A and incloses the burner in the usual manner. The construction of the oil heater is conventional and no claim is laid to it.

The invention comprises a flame extinguishing ring or snuffer 1 which fits loosely around the exterior of the wick tube C above the top of the oil reservoir B, and is adapted to slide longitudinally of the wick tube. The top of the extinguishing ring 1 is normally just below the top edge of the wick tube so as not to interfere with the flame, and is normally held in this position by a pair of diametrically disposed weights 2 which lie loosely upon diametrically extending and longitudinally disposed arms or shelves 3 which are connected integrally or in any other suitable manner to the extinguishing ring 1. The weights are identical in size, so as balance on the ring 1, and

their combined weight is just sufficient to hold the extinguishing ring 1 below the top edge of the wick tube against the action of a light coil spring 4, which is interposed between the ring 1 and the top of the oil reservoir B. It will thus be obvious that if the weights 2 are removed or knocked from the shelves 3 as by tipping over the oil heater or dropping it, the spring 4 will immediately force the extinguishing ring upwardly. The upward movement of the ring 1 is stopped by a cap ring 5 which is secured to and surrounds the member F of the burner above the flame spreading flange I, the said cap ring 5 being formed in two semicircular sections 5^a having upturned ends 6 which are connected by bolts 7 so that the cap ring can be quickly and easily applied to the member E. The width of the extinguishing ring 1 is such that when it engages the cap ring 5 the extinguishing ring bridges and covers the space between the top of the wick tube C and the cap ring 5, the stop ring 5 serving as a cap for the top of the extinguishing ring. It will thus be seen that a substantially air tight chamber 8 is formed above the wick between the extinguishing ring 1 and the member E so that there is insufficient air for combustion, and the extinguishing ring 1 will be positively held against the cap ring 5 by the spring 4 so as to maintain the closed chamber until all flame is extinguished. The flame is thus quickly extinguished, and if the heater has been tipped over or dropped there is no danger of the oil in the reservoir catching fire or exploding. To prevent the weights 2 from being displaced from the shelves 3 by minor vibrations the shelves are preferably slightly dished or recessed at 3^a to form side flanges to prevent the weights from slipping off.

The weights 2 are preferably formed of an alloy which will melt at a predetermined temperature, for instance 400° F., so that if the heater becomes overheated the weights will melt and the spring 4 will cause the extinguishing ring to put out the flame as above described.

In the embodiment of the invention illustrated by Figs. 4 to 9, inclusive, the reference character L designates the screw base of a conventional oil lamp burner which is adapted to screw into the neck of a lamp M. A wick tube N passes upwardly through the base L into the combustion chamber formed by the top O and air deflecting cap P of the burner, said wick tube holding a wick Q which is adjustable by conventional means R. The air deflecting cap is provided with the usual slot S in the top thereof to allow the flame to pass out.

In this embodiment of the invention the extinguishing ring 9 is rectangular in shape, and loosely surrounds the wick tube N, the

ring 9 being held in its normal position just below the top edge of the wick tube, as shown in Fig. 5, by means of the weights 10 which lie loosely upon arms or shelves 11 extending longitudinally from opposite ends of the extinguishing ring 9 through the slot 70 S in the air deflecting cap P. The weights 10 hold the extinguishing ring down against the action of a light coil spring 12 which surrounds the air deflecting cap P and engages the underside of the arms 11. A flame 75 extinguishing cap 13 is pivotally secured in any suitable manner, as at 14, to one side of the extinguishing ring 9 and is adapted to extend over and close the top of the extinguishing ring 9 to put out the flame of the 80 burner. This cap 13 is influenced by a spring 15 which tends to swing the cap over the top of the extinguishing ring 9, but when the extinguishing ring is in an inoperative position, as shown by Fig. 5, the outer 85 side edge of the cap 13 engages the side wall of the wick tube N so as to be held away from the top of the extinguishing ring 9. When the weights 10 are displaced from the arms 11 the spring 12 forces the extinguishing ring 90 upwardly, and as the top thereof passes the top of the wick tube, the spring 15 will force the cap 13 over the top of the extinguishing ring to form a substantially air tight chamber about the wick Q, as shown by Fig. 8, 95 so as to prevent combustion and extinguish the flame. Upward movement of the extinguishing ring will be limited by the top of the air deflecting cap P. As described in connection with the invention as illustrated 100 by Figs. 1 to 3, inclusive, the weights 10 are preferably formed of an alloy which melts at a predetermined temperature, so as to allow the spring 12 to cause the extinguishing ring to put out the flame if the lamp becomes overheated.

It will be seen that the invention is adapted to be applied to any conventional type of oil heater or lamp without any modification or change in the construction of the heater 110 or lamp, and the device can thus be applied to and sold with the heater or lamp, or attached to an old one in use.

It will also be obvious that various modifications and changes can be made in the 115 construction of our device without departing from the spirit or scope of the invention, and we do not wish to be understood as limiting ourselves except as required by the following claims when construed in the light 120 of the prior art.

Having thus described the invention, what we claim is:

1. In a device of the character described, the combination with a wick tube and a 125 flame spreader above the same, of an extinguishing ring surrounding the wick tube and normally below the frame thereof, said

extinguishing ring being vertically movable on said wick tube, means arranged at diametrically opposite points for holding said extinguishing ring in normal position, said holding means being released to allow the extinguishing ring to rise on said tube when the burner is abnormally jarred or tipped over, a cap ring adjustably secured to the flame spreader above the flame, and means for actuating said extinguishing ring into engagement with said cap ring when the said holding means is released.

2. In a device of the character described, the combination with a wick tube and a flame spreader above the same, of an extinguishing ring surrounding the wick tube and normally below the flame thereof, said extinguishing ring being vertically movable on said wick tube, means arranged at diametrically opposite points for holding said extinguishing ring in normal position, said holding means being released to allow the extinguishing ring to rise on said tube when the burner is abnormally jarred or tipped over, a cap ring detachably secured to the flame spreader above the flame, and means for actuating said extinguishing ring into engagement with said cap ring when the said holding means is released.

3. In a device of the character described, the combination with a wick tube and a flame spreader above the same, of an extinguishing ring adapted to surround the wick tube, a cap ring adapted to be detachably secured to the flame spreader above the flame, said cap ring comprising complementary detachably connected arcuate sections to surround the flame spreader, and means for actuating said extinguishing ring into engagement with said cap ring to form an air tight chamber around the flame when the burner is abnormally jarred, tipped over, or becomes over heated.

4. In a device of the character described, the combination with a burner tube, of an extinguishing member, a fusible weight mounted in said extinguishing member to hold the said member in normal inoperative position, said weight being fused and melted when the burner reaches a predetermined temperature, and means for actuating said extinguishing member to extinguish the

flame when said weight is melted from the ring.

5. In a device of the character described, the combination with a burner tube, of an extinguishing ring surrounding the burner tube and normally below the flame thereof, said extinguishing ring being vertically movable on said burner tube, a fusible weight mounted on said extinguishing ring to hold the said ring in normal inoperative position, said weight being fused and melted when the burner reaches a predetermined temperature, and means for actuating said extinguishing ring to extinguish the flame when said weight is melted from the ring.

6. In a device of the character described, the combination with a burner tube, of an extinguishing ring surrounding the burner tube and normally below the flame thereof, said extinguishing ring being vertically movable on said burner tube, a pair of balanced fusible weights mounted at diametrically opposite points on said extinguishing ring to hold the said ring in normal inoperative position, said weights being released from said extinguishing ring when the burner is abnormally jarred, tipped over or reaches a predetermined temperature, and means for actuating said extinguishing ring to extinguish the flame when said weights are released or melted from the extinguishing ring.

7. In a device of the character described, the combination with a burner tube, of an extinguishing ring surrounding the burner tube and normally below the flame thereof, said extinguishing ring being vertically movable on said burner tube, said ring being provided with oppositely extending horizontal weight-receiving arms, a fusible weight loosely mounted upon each of said arms to hold the said extinguishing ring in normal inoperative position, said weights being displaced or melted from said arms when the burner is abnormally jarred, tipped over or reaches a predetermined temperature, and means for actuating said extinguishing ring to extinguish the flame when the said weights are released or melted from the extinguishing ring.
